PRINTING STENCIL

Georges Kanitz, Caracas, Venezuela

Application April 19, 1947, Serial No. 742,615

6 Claims. (Cl. 101—128.2)

1

This invention relates to new and improved printing stencils and has particular relation to new and improved stencils adapted to be used in the so-called screen process and to a method of preparing such stencils.

The main object of my present invention is to provide a stencil for the screen process, which shows a true and exact reproduction of the design to be printed and can be easily and conveniently produced.

Another object of my present invention is to provide a stencil for screen process-printing by copying the design directly to the stencil layer without the disadvantage of the so-called "mesh-marks."

A further object of this invention is to produce a stencil for screen process-printing by first providing the screen with a suitable layer which is not sensitive to light, applying the design to be printed directly to this layer which is subsequently rendered sensitive to light and then insoluble by exposure to light but only in those portions of the same which are not covered by the design, whereupon the soluble portions of said layer, which are covered by the design and the design proper are removed by dissolution of the soluble portions of the stencil layer and the stencil is ready for use.

Other objects and the advantages of the invention will be apparent from the following specification and claims and the appended drawings which illustrate, by way of example, some preferred embodiments of the invention, and in which

Figure 1 illustrates diagrammatically in top view a stencil embodying the present invention;

Figure 2 is a sectional view along line 2—2 of Figure 1;

Figure 3 illustrates a part of Figure 2 on an enlarged scale before "developing," and Figure 4 is a view similar to that of Figure 3, after "developing."

Referring now to the drawings in detail, 1 is a square frame, which may consist of wood or metal, and to which a silk screen 2 of the customary type is applied by stretching in the usual manner. 3 denotes a design, and 4 denotes the material of the stencil before, and 5, after, the developing step.

In carrying out my invention, the solution of a suitable transparent, colloid material, for example an aqueous 10% solution of glue or gelatine is applied to the screen in order to fill the holes of the screen and form a layer of about 0.3 to 0.5 mm. thickness. The coated screen is dried at

a temperature of, for example, 15° to 25° C., and is then brought in contact with the original design to be reproduced and a reproduction is produced on the surface of the dried colloid layer by 5 painting or drawing, as indicated in Figures 1 and 2. The design may be of any type, i. e. it may, for example, consist of printed types or a drawing or the like. In preparing the design to be reproduced on the stencil layer, I prefer the 10 use of inks, pigments or drawing crayons or the like, which are impermeable to light. After the said reproduction on the stencil layer has been made and dried, said layer is treated with a hardening or sensitizing solution, for example an 15 aqueous 2-4% solution of ammonium bichromate and then dried, in order to render the stencil layer substantially uniformly sensitive to light. If a sensitizing solution has been used, the surface of the stencil layer, which carries the reproduced 20 design, is now exposed to a strong light source and after sufficient exposure, developed with warm water. During this developing, those portions of the stencil which are covered by the design and, therefore, have not been affected by the exposure 25 to light, are dissolved, and the drawing adhering to these portions, is also removed from the stencil, thus leaving screen holes forming a registering design, open as indicated in Fig. 4. In contrast to this, those portions of the stencil which were 30 not protected from light by the design and became hardened and insoluble by the exposure to light are not removed by water. They adhere to the screen and keep the holes thereof sealed. Thus, after developing and drying, the stencil is 35 ready for use.

According to a modification of my invention, reproduction of the design to be printed may be produced on the stencil layer by means of inks or lacquers or the like, which are permeable to light 40 but impermeable to the sensitizing solution. After the reproduction of the design to be printed on a surface of the stencil layer by means of an ink or other material of the before-mentioned type, the surface bearing the reproduced design 45 is treated with a sensitizing solution, and, after drawing, said surface is exposed to light and then developed with warm water. Owing to the fact that the ink or the like used in reproducing the design is impermeable to the sensitizing solution, 50 the portions of the stencil layer covered by the design are not sensitized and not affected by the exposure. These portions and the design covering them, are, therefore, removed by the developing step. The developed stencil is dried and is 55 then ready for printing.

According to another embodiment of my invention, developing of the stencil layer is effected by means of a solution which is capable of hardening and rendering substantially insoluble or difficultly soluble the material of the stencil layer. In using such a hardening solution, the design is applied in a manner substantially identical to that described above, but by means of an ink or the like which is impermeable to said hardening solution. After application of the design to the stencil layer, the surface of the latter, which carries the design, is treated with a suitable hardening solution and then permitted to dry. In this treatment, those portions of the stencil layer which are permeated by the solution become insoluble or difficultly soluble. After drying, those parts of the stencil layer which have been protected from the hardening solution by the impermeable design are dissolved by means of a solvent, for example, moderately warm water, and are thus removed together with the design.

According to my invention the screen is completely filled with the stencil material prior to the reproduction of the design on it. I prepare the reproduction on a substantially smooth surface and obtain sharp contour lines substantially without any mesh-marks. Furthermore, in contrast to prior processes, I can use stencil layers of considerable thickness, which completely fill the holes of the screen, or may even form a thicker layer, and avoid or substantially reduce the formation of air bubbles in the stencil layer. In carrying out my invention, it is always essential that by reproducing the design directly on the stencil layer prior to sensitizing or hardening, the lines of the design are in intimate contact with the stencil layer. This results in true and exact reproductions and greatly facilitates true reproduction of fine details.

It will be apparent that my present invention is not limited to the specific details and steps disclosed and may be carried out with various modifications. For example, instead of the above described solution of glue or gelatine, other colloid solutions which are adapted to form a transparent layer substantially without the formation of bubbles and can be sensitized to light, and other sensitizing solutions and various hardening solutions may be used. For example, layers of fish glue or gelatin may be hardened and rendered insoluble by the action of a 5-6% aqueous solution of chrome alum, or a 40% aqueous formaldehyde solution, or an aqueous solution containing about 40% formaldehyde and about 5% phenol. As further examples of stencil materials, shellac, collodium, fish glue and transparent synthetic plastics, and as examples of other sensitizing solutions, other compounds of chromium, such as potassium bichromate may be mentioned. These and other modifications may be made without departing from the spirit and scope of the invention as defined in the appended claims.

The term "design" is used in the present specification and claims to denote the letters, words, drawings or the like to be printed.

What I claim is:

1. A process for preparing stencils for screen printing, said process comprising providing a stretched screen with a soluble stencil layer insensitive to light, applying a design to be printed directly to the surface of said layer, rendering those portions of the layer which are not covered by the design, insoluble by sensitizing and exposure to light, and removing the portions of the layer covered by the design and said design by dissolving these portions of the layer.
2. A process for preparing stencils for screen printing, said process comprising providing a stretched screen with a soluble stencil layer insensitive to light, applying a design to be printed directly to the surface of said layer by means of a painting or drawing material impermeable to light, rendering those portions of the layer which are not covered by the design insoluble by sensitizing said layer and exposing to light the surface carrying the design, and thereafter removing the portions of the layer covered by the design and said design by dissolving these portions of the layer.
3. A process for preparing stencils for screen printing, said process comprising providing a stretched screen with a soluble stencil layer insensitive to light, applying a design to be printed directly to the surface of said layer by means of a printing or drawing material which is impermeable to sensitizing solutions, rendering those portions of the layer which are not covered by the design sensitive to light by treating the surface of the layer carrying the design with a sensitizing solution and then rendering those portions of the layer which are not covered by the design insoluble by exposure to light, and removing the portions of the layer covered by the design and said design by dissolving these portions of the layer.
4. A process as claimed in claim 2, in which the stencil layer consists of a dried solution of glue and sensitizing is effected by means of a solution of ammonium bichromate.
5. A process as claimed in claim 3, in which the stencil layer consists of a dried solution of glue and sensitizing is effected by means of a solution of ammonium bichromate.
6. A product adapted to be used in the preparation of stencils for screen printing, said product comprising a screen and a stencil layer applied directly to said screen, said layer consisting of portions registering with the design to be printed, which are not light-sensitized, and residual portions which are light-sensitized.
